(54) **LOOM TEMPLES**

(76) Inventor: **Philo C. Curtis**

Philo C. Curtis
Letter Patent

The Vehicule referred to in these Letters Patent and making part of the same containing a description in the words of the said Philo C. Curtis himself of his improvement being machinery for templing cloth. The construction of the above specified templer is as follows. I form two wheels, one of which is constructed with moveable arms that can rise and fall as much as is necessary to allow a spur that is placed in the underside of the arm near the centre to take hold of the cloth after the end of the arm has passed over the selvage. This wheel lies in an inclining position directly over a fixed arm wheel which lies horizontally under the selvage of the cloth, and projects enough beyond to receive the end of the moveable arms which are kept from falling into it by the centre until they pass over the selvage, after which they are raised and work together, similar to egg whisks. The cloth resting upon the lower wheel prevents its escaping from the spur in the arms of the upper wheel. The projecting of the fixed arm wheel below the arms is formed into a salient wheel for the purpose of turning the templer as fast as is necessary without injury to the selvage. The wheels are supported in their proper position by means of an iron plate about 3 inch x square, near one edge of which there is a round stud that supports the lower wheel near the opposite edge there is a stand that rises over the lower wheel and supports the upper one. The plate is bolted on to a small bar of iron or iron that is made fast to the breast beam between the breast beam and lath, which is sufficiently elastic to allow the templer to move as much as is necessary to favor the spring of the cloth there is a connection from the templer to the lath by means of a strap and

or wire in such a manner, that when the lattice is drawn back the temples will always stand the same distance from it; but as it moves forward, the temples are allowed to move with the cloth, so that when it is necessary for the temples to turn, the cloth will carry them sufficiently back for the hand which is made fast to the breast beam to take a notch in the notched wheel; then as the lattice is drawn back it carries the centre of the wheels towards it, while the edge is held fast, which causes them to move forward on the selavage without injury to it; the size of the wheels and number of arms, may be varied; the size best calculated for common use, is about 13 inches in diameter with 20 arms; the body of the top wheel should be about 1 inch and 5 eighths in diameter, and three fourths of an inch thick; this wheel has a groove for each arm, running towards the centre, and nearly to it on the upper side, and about one fourth of an inch toward it on the under side; the arms are made with a butt on one end, the other end is fitted into the groove of the wheel so as to move easy; these arms have a small hole through the end that goes in the groove, through which there is a wire ring, passed that is sunk in the upper side of the wheel to keep the arms in their proper places.

In order to set these temples to work, it is necessary to have two sets of wheels, one set for each selavage; they should be placed as near the web as they can be, without interfering with it. What I claim as my invention or discovery in the above specified temples, consists in the construction of a moveable arm wheel with spurs, that are properly adjusted in the selavage by the arms as the wheel turns on its axis; likewise a male wheel calculated to support the selavage and serve as a ratchet wheel to move them both by the power of the lattice together with the notches.

United States Patent

Patent No.: X4149

method for moving, rotary templet by means of a ratchet wheel with a fall or hand acting on it, and a connection with the Earth
